HYDRAULIC CONTROL DEVICE

Walter Ernst, Mount Gilead, Ohio, assignor, by
mesne assignments, to The Hydraulic Press
Corporation, Inc., Wilmington, Del., a cor-
poration of Delaware

Application May 5, 1933, Serial No. 669,493

6 Claims. (Cl. 137—153)

My invention relates to hydraulic control devices, and especially to such devices which are adapted to by-pass the motive fluid in a hydraulic circuit when the pressure in the circuit reaches a predetermined amount.

An object of my invention is to provide a hydraulic control device for regulating a hydraulic circuit, this control device being sensitive to small changes in the volume of the fluid passing through the device.

Another object is to provide a hydraulic device which makes use of an independent differential lifting area to operate the controlling plunger, which area may be of any desired size without being affected by the area required to release the pressure.

Another object is to provide a hydraulic control device wherein the lifting pressure with the plunger valve wide open will be substantially the same as when it is nearly closed, hence providing substantially the same working pressure for large volumes of motive fluid as for small volumes thereof.

Another object is to provide a hydraulic control device wherein light springs with substantially constant resiliency throughout their range of travel may be used to regulate the plunger, instead of stiff heavy springs which have a variable resilience.

Another object is to provide such a device with a graduated valving of fluid, thereby preventing the noise and vibration occurring when the entire valve area is opened at one time.

Another object is to provide such a device wherein fluttering or chattering of the plunger valve through rapid reversals of pressure in the line is effectively prevented by causing the plunger lifting to be effected in a chamber separated from the chamber where the valving action occurs, free backward flow of fluid therebetween being prevented by a retardation device.

Another object is to provide a hydraulic control device which may be used either as an unloader in a hydraulic circuit containing both high pressure and low pressure pumps, or else as a low pressure relief valve in a circuit containing a low pressure pump alone.

Another object is to provide such a device wherein the full pressure is available nearly up to the point of cut-off by reason of the valve pressure being substantially independent of the volume of fluid passed through the valve.

Other objects and purposes will be made apparent from the following description taken in connection with the drawing and appended claims.

In the drawing:

Figure 1 is a diagrammatic view of a hydraulic circuit utilizing my hydraulic control device as an unloader to regulate the low pressure and the high pressure pumps contained in the circuit.

5

Figure 2 is a central vertical section through my hydraulic control device in its preferred form as an unloader.

Figure 3 is a partial central vertical section through my hydraulic control device, showing its 10 preferable modification when used as a low pressure relief valve in a hydraulic circuit containing a low pressure pump.

Figure 4 is a central vertical section through an alternative form of my device adapted for 15 use as a low pressure relief valve.

Figure 5 is a partial vertical section along the line 5—5 of Figure 2, showing a choke valve in the inlet port of the plunger lifting chamber.

Referring to the drawing in detail, in the hydraulic circuit shown in Figure 1, A is a tank for supplying motive fluid to the circuit, B is a low pressure hydraulic pump of a conventional type, and C is a high pressure hydraulic pump, likewise of a conventional type. D is an external view of 20 my device in use as an unloader between the high pressure and low pressure circuits. E is a high pressure safety valve, F is a check valve permitting unidirectional flow only, G is the hydraulic machine, such as a press, to be operated by the circuit, and H is an operating valve for returning the plunger of the machine G to its raised position after its operation has been completed.

Referring now to the details of my hydraulic control device in its preferred form as an unloader (Figure 2), I is a casing joined to a valve housing 2, as by a threaded connection. Reciprocably mounted partly within the casing I and the valve housing 2 is a plunger 3 which is free 25 to move up and down against the pressure of a compression spring 4 which makes contact against the head 5 on the plunger 3. The compression spring 4 may be adjusted to any desired pressure by rotating the adjusting screw 6 30 which pushes the spring cap 7 downward against the compression spring 4. The adjustment is maintained in locked position by the lock nut 8.

Contained within the upper part of the valve housing 2 is a plunger lifting chamber 9 through 35 which the plunger 3 passes. Within this chamber, the plunger diameter is enlarged to form the differential lifting area 10 which is of annular form. One side of the plunger lifting chamber 9 has the inlet port 11 passing through the walls 40

50

55

of the valve housing 2, where it continues in a conduit 12 (Figure 1).

Passing longitudinally through the plunger 3 is a channel 13 permitting the flow of fluid between the interior of the casing 1 and the exhaust chamber 14 below the end of the plunger 3. The exhaust chamber 14 continues in an exhaust conduit 15 by which fluid is returned to the tank A. The lower end 16 of the plunger 3 is tapered 10 as for a purpose which will hereinafter appear.

The valve chamber 17 of the valve housing 2 is joined on one side by a low pressure feed conduit 18 and on the opposite side by an outlet conduit 19. The inlet port 11 in the plunger lifting chamber 9 may be equipped with a needle valve, choke valve or other retardation device in order to impede the backward free flow of fluid from the plunger lifting chamber 9, for a purpose which will likewise later appear. One form of this 15 choke valve is shown in Figure 5. It consists of a conically pointed screw 28 whose threads engage corresponding threads in its housing 29 which is joined to the valve housing 2 by any suitable means such as by the threaded connection 30.

20 The conical tip of the screw 28 partially closes the inlet port 11 in a manner which may be varied by threading the screw in or out and locking it in place with the lock nut 31. To one side of the housing 29 is attached the conduit 12.

25 In the use of my hydraulic control device as an unloader, as shown in Figure 1, the conduit 12 leading to the inlet port 11 in the valve lifting chamber 9 is joined to the high pressure feed line 20 leading from the high pressure pump C. Consequently, the building up of pressure by the pump C within the high pressure feed line 20 will be communicated to the plunger lifting chamber 9.

30 In the use of my hydraulic control device as a low pressure relief valve, the conduit 12 is joined to the valve chamber 17 so that fluid may pass from that chamber to the plunger lifting chamber 9.

35 A very convenient modification for accomplishing the same purpose in a simpler way is shown in Figure 3, wherein the plunger lifting chamber 9 is connected with the valve chamber 17 by a conduit 21 running longitudinally through the plunger 3 and containing the transverse passages 50 22 and 23 leading into the valve chamber 17 and the plunger lifting chamber 9, respectively. A needle or choke valve 24 with a conical point 25 serves to impede the backward flow of fluid from the plunger lifting chamber 9 through the conduit 21 into the valve chamber 17, and is adjusted by turning its threaded portion 26 and tightening the lock nut 27. This modification of Figure 3 enables the communication between the plunger lifting chamber 9 and the valve chamber 17 to be established wholly within the plunger rather than by using external piping, as would be required in the form of my device shown in Figure 2 when used as a low pressure relief valve.

40 In the operation of my hydraulic control device as an unloader, the device D is arranged as shown in the circuit illustrated in Figure 1, previously described. When the pumps are placed in operation, the low pressure pump B discharges 45 straight through the unloader by way of the low pressure feed conduit 18, the valve chamber 17 and the conduit 19, thence through the check valve F into the ram chamber of the hydraulic press G. When the pressure in the press ram 50 chamber builds up to a certain predetermined

amount, as regulated by the compression force exerted by the compression spring 4, the pressure fluid entering the plunger lifting chamber 9 from the high pressure feed line 20 by way of the conduit 12 will exert its force against the differential area 10 of the plunger 3 and lift the plunger. When the plunger rises, it will open communication between the valve chamber 17 and the exhaust conduit 15, causing the fluid to flow from the low pressure pump B through the low pressure feed conduit 18 and the valve chamber 17 into the exhaust conduit 15 and thence through the exhaust line 32 back to the tank A. In this way the output of the low pressure pump B is by-passed into the exhaust line 32, and meanwhile the high pressure pump C builds up pressure in the ram chamber of the press G, being prevented from backing into the low pressure line 19 by means of the check valve F. The high pressure continues to act on the differential area 10 of the plunger 3 and holds this plunger wide open. No power, therefore, is required to bypass the low pressure pump while the high pressure pump is holding pressure.

45 When it is desired to return the press, the operating valve H is opened, connecting the high pressure feed line 20 with the exhaust line 32, thus by-passing the output of the high pressure pump C, and causing the press ram of the press G to return.

50 The presence of the differential area 10 on the plunger 3 serves to permit a very slight pressure to lift the plunger. In an ordinary relief valve or unloader where the pressure works directly against the full area of the plunger and relieves itself by lifting this plunger, the area against which the press will work must always be equal to the area required for the relief, hence requiring a very heavy spring 4 since the pressure works against the full area of the plunger. Such heavy 55 springs are less resilient than light springs, and have a variable resilience during different portions of their compression. Consequently, as a heavy spring 4 is compressed during travel of the plunger, its resilience declines and a higher pressure is required to force the plunger upward during the last period of its travel than at the start. The consequence is that the device with a heavy spring 4 will exert a higher regulating pressure with the plunger valve wide open than with the plunger valve almost completely closed: this in turn means that a small volume of liquid passing through this valve will lift the plunger at a lower pressure than a large volume.

60 This disadvantage is overcome by providing a differential area 10 for lifting the plunger 3 instead of allowing the pressure to be exerted against the full area of the plunger, with the attendant difficulties as described above. By this means the differential area can be made of any desired amount without being affected by the area required to release the pressure, and an independent differential plunger-lifting area is the result. Consequently, a lighter spring 4 may be used for regulating the operating pressure, such light springs having a greater flexibility and more nearly constant resilience during the period of their travel. This in turn means that the pressure required to keep the valve wide open with a large volume of liquid passing through the valve is not substantially different from the pressure required to keep the valve slightly open when a small volume is passing through it. The full pressure is also available nearly up to the point of cut-off.

The operation of the ordinary unloader or relief valve is accompanied by noise and vibration since the entire area of the valve is lifted at once. In my hydraulic control device, however, I have provided the plunger 3 with a tapered end 16. As the plunger rises, the valve will start to open on the high side of the taper and will gradually approach the full opening, thus giving a smooth and graduated cut-off which eliminates such noise and vibration.

In the preferred form of my device, the differential plunger lifting area 10 is placed in a plunger lifting chamber 9 which is separate from the valve chamber 17, and connected therewith by a conduit either having a retarding effect on back flow of liquid by reason of its small diameter or else having a choke valve as previously described. The purpose of this separate chamber for the plunger lifting is to prevent fluttering and chatter of the valve plunger. In the ordinary plunger valve, where the plunger lifting area is in the valve chamber, a drop in pressure occurs when the plunger lifts, this pressure drop immediately producing a re-seating of the valve with a corresponding increase in pressure: this re-seating again causes the plunger to lift with a repetition of the pressure drop. Thus the valve plunger will flutter up and down at a high rate because of the rapid reversals of pressure in the hydraulic circuit. In my hydraulic control device, however, these rapid reversals of pressure in the valve chamber 17 are prevented from reaching the independent plunger lifting chamber 9 because of the choke valve therebetween: this choke valve allows a slow reversal of pressure, but effectively dampens the rapid reversals by obstructing the free backward flow of liquid. The result is that the fluttering is very effectively reduced either completely or to a negligible amount, depending on the adjustment of the choke screws 26 or 28. In small valves the choke screw may be eliminated, a corresponding effect being created by the smallness of the conduit connecting the plunger lifting chamber 9 with the valve chamber 17.

In the operation of my hydraulic control device as a low pressure relief valve, but one pressure is present in the hydraulic circuit, as from the low pressure hydraulic pump B. The pressure flows from the pump B through the valve chamber 11 of the device into the hydraulic mechanism operated thereby. This pressure also reaches the plunger lifting chamber 9 either through the inlet port 11 and a conduit connecting it with the valve chamber 17 (Figure 2) or else through the drilled conduit 21 in the plunger 3 itself (Figure 3), the latter form of which is especially adapted for use as a relief valve. When the pressure in the circuit builds itself up to a predetermined amount, the pressure in the plunger lifting chamber 9 likewise rises and pushes against the differential area 10, causing the plunger to rise against the compression of spring 4 and permitting the liquid entering from the pump B by the conduit 18 to discharge directly into the exhaust conduit 15, thus being by-passed directly without reaching the hydraulic machine being operated.

The modified form of my hydraulic control device shown in Figure 4 is particularly adapted to operate as a relief valve. The differential plunger lifting area is still provided as a means of lifting the plunger 3, yet causing the lifting area 10 to be independent of the working area upon which the hydraulic machine operates. In this case,

however, the differential area 10 on the plunger 3 is in the valve chamber 17, so that the plunger lifting chamber and the valve chamber are combined. This construction eliminates the vibration arising in types of valves where the plunger area is acted upon by the pressure, but lacks the further refinement of preventing fluttering through the use of a plunger lifting chamber which is separate from the valve chamber, and with an impedance of free flow of liquid therebetween. The operation of the modification shown in Figure 4 is otherwise essentially the same as that of the types shown in Figures 2 and 3. The requisite pressure acting on the differential area 10 lifts the plunger, causing the inward flow of fluid through the conduit 18 to be by-passed into the discharge conduit 15 rather than continuing on its way to the hydraulic press or other machine being operated. The modified form of valve in Figure 4, however, likewise has the tapered plunger end 16 which gives a graduated cut-off and consequent reduction of noise.

It will be understood that I desire to comprehend within my invention such modifications as may be necessary to adapt it to varying conditions and uses.

Having thus fully described my invention, what I claim as new and desire to secure by Letters Patent is:

1. A hydraulic control device comprising a valve chamber, a plunger lifting chamber, an exhaust chamber, a plunger passing reciprocably across said valve chamber to close an outlet port therefrom and extending into said plunger lifting chamber, said plunger having a pair of passages therethrough, one passage leading from said valve chamber to said plunger lifting chamber and the other passage leading from said exhaust chamber to a chamber other than the aforementioned chambers, said plunger within said plunger lifting chamber having a differential area adapted to cause reciprocation thereof when acted upon by pressure fluid, and means for conducting pressure fluid from said valve chamber to said plunger lifting chamber.

2. A hydraulic control device comprising a valve chamber, a plunger lifting chamber, a plunger passing reciprocably across said valve chamber to close an outlet port therefrom and extending into said plunger lifting chamber, said plunger within said plunger lifting chamber having a differential area adapted to cause reciprocation thereof when acted upon by pressure fluid, and means for admitting pressure fluid to said plunger lifting chamber from said valve chamber, said means comprising a conduit passing through said plunger between said chambers.

3. A hydraulic control device comprising a valve chamber, an exhaust chamber, a plunger lifting chamber, a plunger passing reciprocably across said plunger lifting chamber to close an outlet port therefrom, said plunger having a differential area adapted to cause reciprocation thereof when acted upon by pressure within said plunger lifting chamber, yielding means adapted to resist the motion of said plunger during its reciprocation, and a chamber for said yielding means, said plunger having a passage leading from said exhaust chamber to said yielding means chamber and an additional passage leading from said valve chamber to said plunger lifting chamber.

4. A hydraulic control device comprising a valve chamber, an exhaust chamber, a plunger lifting chamber, a plunger passing reciprocably

across said plunger lifting chamber to close an outlet port therefrom, said plunger having a differential area adapted to cause reciprocation thereof when acted upon by pressure within said chamber, yielding means adapted to resist the motion of said plunger during its reciprocation, and a chamber for said yielding means, said plunger having a passage leading from said exhaust chamber to said yielding means chamber and an additional passage leading from said chamber to said plunger lifting chamber, said last-mentioned passage having means for adjustably restricting the flow of fluid therethrough.

5. A hydraulic control device comprising a valve chamber, a plunger-lifting chamber apart therefrom, a valve plunger passing reciprocably across said valve chamber to close an outlet port therefrom, said plunger within said plunger-lifting chamber having a projecting piston area, said plunger being arranged to be engaged and urged by pressure fluid in one direction only, means for conducting pressure fluid from said valve chamber to said plunger-lifting chamber, 10 means directly connecting the opposite side of

15

20

25

said plunger to the outlet of said valve and yielding means for urging said plunger in the opposite direction from the direction of motion caused by the engagement and urge of said pressure fluid, whereby to provide substantially the same lifting pressure with the valve plunger wide open as with the valve plunger nearly closed.

6. A hydraulic control device comprising a valve chamber, a plunger-lifting chamber apart therefrom, a valve plunger passing reciprocably across said valve chamber to close an outlet port in the opposite wall thereof, said plunger within said plunger-lifting chamber having a projecting piston area, said plunger being arranged to be engaged and urged by pressure fluid in its open direction only, means for conducting pressure fluid from said valve chamber to said plunger-lifting chamber, means directly connecting the opposite side of said plunger to the outlet of said valve and yielding means for urging said plunger in its closing direction, whereby to provide substantially the same lifting pressure with the valve plunger wide open as with the valve plunger nearly closed.

WALTER ERNST. 25
